SWITCH CONSTRUCTION AND
ARRANGEMENT

Max L. Goldbert, New York, N. Y., and Roy T. Watts, Miami Beach, Fla., assignors to Electric Trading Corporation, New York, N. Y., a corporation of New York

Application March 4, 1935, Serial No. 9,212

6 Claims. (Cl. 175—369)

This invention relates to switch assemblies.

It is an object of this invention to devise a simplified switch assembly which will require fewer parts, which will be easy to assemble and will cut down the number of operations necessary for assembling, which will be sturdy and compact, and which will provide good electric connection with a minimum of joints. Further objects will become apparent in the course of the specification.

10 In the drawings, wherein we have shown an illustrative embodiment of our invention in which three switches are mounted together,

Fig. 1 is a front view of the switch panel;

Fig. 2 is a section taken on line 2—2 of Fig. 1;

15 Fig. 3 is a section of one of the switches, showing its relation to the panel and housing, taken on line 3—3 of Fig. 1;

Fig. 4 is an enlarged detail in perspective of the spacer arrangement;

20 Fig. 5 is a front view of the panel with switches removed;

Fig. 6 is a rear view (turned over on the transverse axis) of the panel with switches removed; and

25 Fig. 7 is an enlarged sectional view taken on line 7—7 of Fig. 5.

Reference character 10 indicates the main panel, of insulation material, on which are mounted the stationary parts of three switches designated generally as 12, 14 and 16. Switch apertures 11 in the panel accommodate the switch rotors 18, each of which comprises a shaft 20, having at one end an enlarged head 21, at the other a knob 24, and two sets of switch points 26 and 28 intermediate the ends.

30 On the front face of the panel 10 is mounted a single conductor strip 30 having three contacts 32. This strip 30 has three holes registering with holes in panel 10, through which hollow rivets 34 are placed and flanged over. It will be observed that this simple construction provides three contact points which are directly connected electrically, securely affixed, and held against turning. The contact blades 32 jut in radially of the 35 apertures 11, but from the blade to the riveting point each angles off to the side. Furthermore, in this same portion, the contact has an offset double bend to space it out from the panel face. This off-set double bend is true of every one of the contacts on both faces.

35 Three individual contact points 36 are secured to the face of the panel, 90° counterclockwise of the three unitary contact points. Each has a hole registering with a hole in the panel, and hollow rivets 38, flanged over, secure them to the panel.

On each of these contact points an arm 40 extends out and has a bent-in finger 42 which fits in a hole 44 in the panel. Thus the single fastening means for each of these contacts serves to attach it to the panel and also secure it in such 5 way as to prevent rotation. As will appear later, it serves another function as well.

180° farther around counterclockwise a similar set of contacts 46 have hollow rivets 48 securing them to the panel, and arms 50 terminating in 10 fingers 52 cooperate with holes 54 to keep these contacts from turning.

On the reverse side of panel 10 is a duplicate set of contact points, the relationship between the contact points on the two faces being indicated by the full and dotted lines in Figs. 5 and 6.

15 The integral metal strip 56 provides contacts 58, and is secured to the panel by hollow rivets 60.

Contact points 62 are secured to the panel by hollow rivets 64, and have arms 66 with bent-in 20 fingers 68 fitting in holes 70 and preventing the contact points from turning. It will be noted that the contact members 62 are angled to the side, between the blade tips and the riveting points, the direction being opposite to that of contact 25 members 32, so that the blade tips of contacts 32 and 62 form aligned pairs at aperture 11, yet their fastening means are spaced and the two contacts are insulated from each other.

Another set of contact points 72 comes opposite 30 the front face set 46, and the same hollow rivets 48 attach both contacts to the panel and electrically connect them to each other. The contacts 72 have arms 74 with bent-in fingers 76 which extend into the same holes 54 which hold 35 fingers 52.

The particular construction of the switch rotors with their switch points is not in itself of our invention, and will not be described in great detail. Suffice it to say that as the rotor shaft 40 is turned, preferably by a snap mechanism interposed between the knob and the shaft, the two sets of switch points 26 and 28 engage and connect various of the contact points, the spring jaws of the switch points sliding on over the knife 45 edges of the contact points and gripping same.

The contact points on the panel are connected to the current source and the various resistance coils or the like which the switch assembly controls, by wire leads, which may be single as 50 shown in Fig. 7 or multi-strand or of some other type. The end of the wire 78 is inserted in the hollow rivet and a ring of solder 79 fused about the wire, the rivet, and the body of the contact member.

5 A rear panel 82 is provided to enclose the switch assembly and to provide journals for the rotor shafts and also to mount a quadrantal spring detent 80 which cooperates with the rotor and any snap mechanism which may be employed in connection therewith.

10 This unit of switches, center panel and rear panel is complete and rigidly fastened together and its spacing relations fixed. It can then be applied to any appropriate housing or other surroundings. For example, there is shown in phantom in Fig. 2 a front panel 84, which in practice would probably be the front casing wall of an electric cooker or other apparatus, and peripheral walls 86. Bolts or other fastening means would clamp the rear panel 82 and the front wall 84 together, with walls 86 between as a spacer and peripheral housing. A U-shaped bracket member 88 is provided for each switch and serves to space 15 the front panel, the main insulation panel, and the rear panel. This member 88 is provided with a central opening 90 which serves as a front bearing for the rotor shaft. The rear panel 82 has an opening 92 for each switch which serves as 20 a rear bearing for the rotor shaft, which is held in position by its head 21. Member 88 has upper and lower shoulders 94 which bear against the front face of the panel 10. Narrowed portions 96 extend through slots 98 in panel 10 and on 25 through slots 100 in panel 82 where the projecting ends are split, headed, or otherwise secured, as illustrated at 101. Between panel 10 and panel 82 a spacer member 102 is provided on each arm 96 to space panels 10 and 82 apart. This spacer member 102 which is most clearly seen in Fig. 4, is U-shaped and has slots 104 and 106 at the bends through which portion 96 of member 88 30 extends.

35 It will thus be seen that the shoulders 94 and the heads 98 limit separation of the center panel and the rear panel, and the spacer members 102 hold the said panels apart, giving a rigidly fixed structure. It will be realized that while an assembly of three switches has been shown, the 40 invention is not limited to this number but is applicable to any plurality of switches and in part is applicable to a single switch. Furthermore, this assembly construction can be used in connection with any of a great number of types of 45 electrical apparatus. In actual commercial practice it has been found that the carefully worked out construction here disclosed has effected important economies in manufacture while giving advantages over other constructions in simplicity, ease of assembly, sturdiness and good 50 electric contact and conductivity.

55 Accordingly we wish our invention not to be limited to the exact disclosure hereof, but only by the scope of the appended claims.

60 We claim:

1. In an electric switch assembly, an insulation panel having two apertures therein, an apertured contact point mounted on one face of said panel, a second apertured contact point mounted on the other face of said panel, a hollow rivet passing through the apertures of both contact points and the first aperture in the panel, and being headed at each end, and an arm extending out from each contact point and having a bent-in end portion, both of said bent-in end portions fitting in the second panel aperture, and a conductor wire fitting in said hollow rivet whereby to make electrical connection with both contact points.

2. In a switch assembly, an insulation panel,

a contact member, a hollow attaching member, and a conductor lead, said panel having two apertures, said contact member having an aperture, a blade portion, and an arm portion extending out from the aperture and terminating in an inwardly bent portion, the contact member aperture and one of the panel apertures being aligned and the attaching member passing through both and being flanged out at both ends, the bent over end of the contact member arm fitting in the second panel aperture, and the conductor lead extending into the hollow of the attaching member and being soldered thereto.

3. In a switch assembly, an insulation panel having an aperture therein for a switch rotor, adjacent said aperture on one face of said panel a contact member having a blade portion jutting in radially over said aperture and a portion angling to the side of said radial line, an attaching means extending through said angled portion of the contact member and through the panel, on the other face of said panel a second contact member having a blade portion jutting in radially over said aperture axially opposite the first-mentioned contact blade and having a portion angling to the side of the radial line in the opposite direction from that of the contact member on the first face, and an attaching means extending through said angled portion of the contact member and through the panel, the relative shape of the parts being such that there is no contact between the two contact members or their attaching means.

4. In a switch assembly, an insulation panel, a back panel, a bar passing through apertures in both panels and having shoulders outside of one panel and an enlarged head outside of the other panel, a U-shaped spacer member between the panels, said spacer member having an aperture in each bent over end portion, said bar passing through said apertures, the relative dimensions of the spacer member and the bar being such as to hold the two panels at a definite distance from each other.

5. In a switch assembly, an insulation panel, a back panel, a pair of apertures in each panel, a switch shaft journal in the rear panel, a U-shaped bracket member having a center portion spaced forward of the insulation panel and having a journal for the switch rotor shaft therein, and having two arm portions extending through the apertures in both panels, shoulders on the arm portions abutting against the front face of the insulation panel, enlarged heads at the ends of the arms immediately outside of the rear panel, and spacer members about the portions of the arms between the panels.

6. In a switch assembly, a front panel, a center insulation panel, and a rear panel, a bracket member extending through the center and rear panels and having abutments outside both of said panels whereby to space them against moving farther apart, the front end of said bracket member extending out from the center panel and abutting against the front panel, spacing same from said center panel, and a spacer member between the center and rear panels to space them against moving closer together, said bracket member passing through an aperture in said spacer member.
